GOLF GAME DEVICE

Stanley Halpern, 295-16 86th Road, Hollis, N.Y., and Joseph Halpern, 810 Howard Ave., Brooklyn, N.Y.

Filed Oct. 31, 1962, Ser. No. 234,487

2 Claims. (Cl. 73-379)

This invention relates generally to golf games and more particularly to a miniature golf game for use in the back yard of a home.

A principal object of the present invention is to provide a portable miniature golf game that can be set up in the back yard of a home, in a park or the like, affording the player all of the exhilarations and thrills of the regulation outdoor game of golf.

Another object of the invention is to provide an outdoor golf driving range that is adapted to be set up in the back yard of a home.

A further object of the invention is to provide an outdoor golf game adapted to be marketed in kit form convenient for assembly and storage.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a top plan view of the game apparatus shown in position on the ground in the back yard of a home, parts being broken away to indicate length.

FIG. 2 is a similar view showing the position, in full lines, of the weighted ball and golf ball after being played, possible positions of the weighted ball being shown in dotted lines.

FIG. 3 is a perspective view of the game apparatus, showing the golf ball teed up.

FIG. 4 is a side elevational view thereof showing the golf ball teed up.

FIG. 5 is a top plan view of the protractor used in the game.

FIG. 6 is a top plan view of the golf ball used in the game.

FIG. 7 is a top plan view of the weighted ball used in the game.

FIG. 8 is a side elevational view of the pole and flag used in the game.

FIG. 9 is a top plan view of the measuring tape used in the game, parts being broken away.

FIG. 10 is a perspective view of a stack of score and plotting cards used in the game showing a tape and protractor in operative position in dot-dash lines.

FIG. 11 is a top perspective view of the kit with the game apparatus therein, the cover of the kit being shown in open position, parts being broken away.

FIG. 12 is a top plan view of a protractor and ruler unit used in the game.

Referring in detail to the drawings, in FIG. 1 a golf game apparatus embodying my invention is shown in operative position on the ground in the back yard 10 of a home, the game apparatus being indicated generally at 12. The game apparatus includes broadly a measuring tape 14, a protractor 16, a weighted ball 18 and a golf ball 20 attached to the weighted ball by a rope or reinforced nylon cord 22. A pole 24 with flag 25 thereon indicates the position and number of the golf hole, respectively. The golf ball 20 is to be struck and driven by a golf club 21 used by the player in the ordinary manner. A separate protractor 27 and ruler 29 are used to plot the necessary distance and direction to the hole after the drive.

The tape 14 is flexible and flat and provided with grad-

2

uations 26 on one surface thereof, the graduations indicating yardage, beginning with 50 yards and ending with 410 yards, the weight of the rope representing 50 yards. One end of the tape is pivotally attached to the crosspiece 28 of the protractor 16 by means of a pivot pin 30 extending through a hole in the crosspiece. The semicircular portion 32 of the protractor is graduated in degrees from 0° at its center to 90° on both sides thereof.

The weighted ball 18 is used to indicate the distance travelled by the driven golf ball 20. The weighted ball is attached to the rope 22 by tying one end of the rope to a U-shaped staple 36 secured to the surface of the ball 18 opposite its flat side 38. The other end of the rope is tied to a U-shaped staple 40 secured to and protruding from the surface of the golf ball 20.

The pole 24 has a pointed end to facilitate driving it into the turf and the flag 25 supported thereby bears indicia giving the number of the hole, for example "3" as shown in FIG. 8.

The protractor 27 is calibrated in degrees from "0" at the center to "90" on each side thereof. The ruler 29 is calibrated in yardage from "0" to "550" yards.

The game apparatus 12 and necessary paraphernalia are marketed in a kit indicated generally at 44 in FIG. 11. The kit 44 comprises a rectangular shallow box 46 of cardboard, open at the top and provided with a hinged cover 48. A false bottom 50 is supported on the bottom wall 52 of the box by means of downwardly extending side and end flanges. A round hole 54 is formed in the false bottom to receive the weighted ball 18. Another round hole 58 is formed in the false bottom to receive and hold the golf ball 20. A pair of closely spaced upstanding flaps 60, 60 is formed in the false bottom adjacent the holes 54 and 58 to hold in position a round elongated stick 62 around which the rope 22 is wound, the ends of the rope being attached to the weighted ball and golf ball. The protractor 16 rests flatwise on the false bottom and is held thereon by an elastic band 64, the attached tape 14 in wound condition being positioned in a round hole 66 formed in the false bottom adjacent the protractor. The pole 24 is held flatwise on the false bottom by an elastic band 68. A plurality of other poles 70 with flags 72 are held in flatwise condition on the false bottom by elastic bands 74. The flags 72 bear indicia indicating distance in feet. A supply of tees 76 for mounting the golf ball on the ground is positioned on the false bottom and held by elastic bands 78. A supply of rectangular-shaped paper sheets 80 is stacked and held positioned between upstanding flanges 82 upstruck from the material of the false bottom. The sheets 80 bear indicia indicating the number of the hole being played, for example, hole 3, and indicating the yardage, for example, 240 yards, and the par, for instance par 3. The shape of the fairway of the hole is shown in outline and a space occupied by the tee and a space occupied by the green are also indicated. Nine of such sheets, one for each of nine holes, may be supplied, or eighteen if desired.

A stack of paper score cards 84 is piled up on the false bottom and held in position by an elastic band 85. When the equipment and paraphernalia of the game apparatus are mounted and held on the false bottom, the cover 48 of the box readily fits thereover, in closed position.

In playing the game, the apparatus is moved from the kit and the protractor 16 laid on the ground of the back yard and nailed in position in a flatwise condition. The attached measuring tape 14 is then extended, across the semicircular portion 32 of the protractor, over the "0," for the entire length of the tape. At the free end of the tape, the pole 24 with flag 25, is driven into a selected portion of flat ground in the back yard suitable for putting, the pole indicating the position of the hole which

is being played, and the flag indicating the number of the hole being played. The weighted ball 18 is then placed on the protractor over the pivot pin 30 and the rope 22 extended in a direction opposite to the direction of extension of the tape 14 as shown in FIG. 1 in line with the tape, the golf ball 20 attached to the other end of the rope being teed up on a tee 76 inserted into the ground. The object of the game is to drive the weighted ball 18 along the flat tape 14 to the hole indicated by the pole 24 in the least number of strokes or shots. This is done by striking the golf ball 20 with the golf club 21 in the usual manner and driving the golf ball into the air in the direction of the arrow which drives the weighted ball along the tape 14 and pulls the weighted ball 18 over and along the tape 14 toward the hole indicated by the pole 24.

The distance the weighted ball 18 has been driven is indicated by the graduations on the tape 14, the tape being placed over the driven weighted ball for this purpose. For example, the weighted ball 18 shown in FIG. 2 has been driven 250 yards in a straight line toward the hole numbered "3" indicated by flag 25 on pole 24.

The protractor 16 will indicate any deviation from the straight line. For example, if the golf ball 20 is driven to the right of the arrow shown in FIG. 1, as indicated in dotted lines in FIG. 2, then the tape 14 will have been pulled by the golf ball to the right of the "0" mark on the protractor 16 and the degree of pull or deviation is indicated by the graduations on the semicircular portion 32 of the protractor. This deviation represents a "slice" 30 in the jargon of golf. If the golf ball is driven to the left, for example, as indicated in dotted lines in FIG. 2, then the tape 14 will have been pulled by the golf ball to the left of the "0" mark on the protractor 16 and the 35 degrees of pull or deviation is indicated by the graduations on the semicircular portion of the protractor. This deviation to the left represents a "pull" in the jargon of golf.

As each shot is taken, the distance the weighted ball 18 is driven and the angle of direction of the drive, if 40 any, are plotted on the appropriate sheet 80 by means of the ruler 29 and protractor 27. After the first shot is taken, the driven weighted ball 18 is returned to its initial position on the pivot pin 30 of the protractor 16, and the golf ball 20 is returned to its initial position in 45 line with the tape 14 behind the protractor. The golf ball 20 is again hit with the club 21 in an effort to drive the weighted ball 18 the remaining distance to the hole as indicated by the flag 25, for example, 160 yards as shown in FIG. 2. The distance the weighted ball 18 has been driven by the second shot is plotted on the sheet 80 by means of the ruler 29 and protractor 27. Such shots continue until the weighted ball 18 reaches the putting green G. A conventional golf ball may then be placed on the green at the point where the weighted ball 18 is 50 located and the conventional ball putted into the hole formed in the green.

If, for example, the weighted ball 18 had been driven 250 yards on the first drive but sliced to the right or pulled to the left as shown in dot-dash lines in FIG. 2 approximately 10 degrees as shown by the protractor 16, then in that event the distance driven and the degree off center would be plotted on the sheet 80 by the ruler 88 and protractor 86. The weighted ball 18 would then be returned to its initial position on the pivot pin 30 protractor and 60 the golf ball 20 returned to its initial position. The golf ball 20 would again be hit by the golf club 21 and the

distance the weighted ball 18 is driven thereby and the angularity of the shot are plotted on the sheet 80. Such procedure is followed after each shot until the weighted ball 18 reaches the green G when a conventional golf ball is substituted for the weighted ball 18 and the substituted ball putted into the hole in the green. The score for each hole played is kept on the score card 84.

As in regulation golf, the player who shoots the total number of holes played, for example, nine or eighteen, or 10 any selected number, in the least number of strokes or shots wins the game.

While we have illustrated and described the preferred embodiment of our invention, it is to be understood that we do not limit ourselves to the precise construction herein disclosed and that various changes and modifications may be made within the scope of the invention as defined in the appended claims.

Having thus described our invention, what we claim as new, and desire to secure by United States Letters Patent is:

1. A game apparatus comprising an elongated flexible tape with graduations on one surface thereof representing yardage, a semicircular protractor pivotally connected to one end of the tape, said protractor having graduations representing degrees of angularity relative to the center of the semicircular body thereof, said tape adapted to extend across said graduations, a weighted ball movably positioned on the pivotal point of the protractor, a rope tied at one end to said weighted ball, a golf ball tied to the other end of the rope whereby upon striking of the golf ball with a golf club the weighted ball is moved along the tape, the graduations indicating the distance in yards travelled by the weighted ball, and a pole at the free end of the tape providing a target for the golf ball when struck.

2. A game apparatus comprising an elongated flexible tape with graduations on one surface thereof representing yardage, a semicircular protractor pivotally connected to one end of the tape, said protractor having graduations representing degrees of angularity relative to the center of the semicircular body thereof, said tape adapted to extend across said graduations, a weighted ball movably positioned on the pivotal point of the protractor, a rope tied to one end to said weighted ball, a golf ball tied to the other end of the rope whereby upon striking of the golf ball with a golf club the weighted ball is moved along the tape, the graduations indicating the distance in yards travelled by the weighted ball, and a pole at the free end of the tape providing a target for the golf ball when struck, and a separate protractor and ruler unit for plotting the distance the weighted ball is driven and its direction after the drive.
